UNITED STATES PATENT OFFICE.

ACHILLES FORTINA, OF RICHMOND, CALIFORNIA.

SCAFFOLD.

Application filed March 30, 1926. Serial No. 98,429.

This invention relates to scaffold structures.

It is the principal object of the present invention to provide a generally improved scaffold structure which is of simple and inexpensive construction and particularly adapted for use when repairing railway cars, which scaffold structure is provided with a vertically movable platform which may be disposed in any one of a plurality of elevations and latched to prevent it from accidentally lowering.

In carrying out this object I provide a scaffold structure which is constructed in two units arranged upon opposite sides of a trackway, so that a railway car to be repaired or painted may be disposed therebetween. Each scaffold structure is fitted with a vertically movable platform which may be disposed in either of a plurality of elevations. Latching means are provided which are operative from the platform to securely latch the platform in either of its elevations and prevent it from accidentally lowering.

One form which the invention may assume is exemplified in the following description and illustrated by way of example in the accompanying drawings, in which:

Fig. 1 is a side elevation of a scaffold structure embodying the preferred form of my invention with parts in section to more clearly disclose certain features of construction.

Figure 2 is an end view showing the scaffolding arranged at the sides of a trackway.

Fig. 3 is a fragmentary view disclosing the construction of the latch mechanism for maintaining the platform at the desired elevations.

Fig. 4 is a fragmentary view in plan section taken on line IV—IV of Fig. 1 of the mechanism disclosed in the preceding figure.

Referring more particularly to the accompanying drawings, 10 generally indicates a scaffolding structure for use in railway repair shops when repairing or painting railway cars. The scaffold structure is here disclosed as being a permanent structure. It may, however, be constructed so that it may be transported from place to place.

In the present instance I have shown the scaffold structure as being constructed in two units 11 which are arranged at opposite sides of a trackway 12, so that the car to be re-

paired or painted may be positioned directly between them and within working position of the platforms 14 of the scaffolds. The platform 14 of each scaffold unit is capable of being held at three different elevations, which have been found sufficient for all purposes in connection with railway car repair work.

Reference being had to Fig. 1 it is seen that each scaffold unit comprises a pair of vertical columns 15 which are spaced a distance apart substantially equal to the length of a railway car and supported by piers 16. The upper ends of the columns 15 are connected by a horizontal beam 17. The columns 15 are tubular and each receives a platform guide 18. At their lower ends the platform guides 18 are rigidly connected by braces 18^a to the horizontally disposed platform 14 arranged on the inner side of the scaffold. At their upper ends the guides 18 are fitted with transverse latch bars 20 which project horizontally and outwardly through elongated slots 21 formed in opposite sides of each column 15. The length of these slots 21 is sufficient to permit the guides 18 and the platform 14 to travel its maximum vertical movement. When the platform is positioned at its lowermost position the horizontal braces 18^a, which connect the guides 18 to the platform 14, rests in the lowermost ends of the slots 21 and support the platform at a distance above the ground.

It is intended that the platform 14 may be disposed at three elevations, one of which has been mentioned, the other two being at points where the bars 20 of the guides 18 will engage the ends of pivotal latch levers 23. A pair of these levers 23 being pivotally connected to each column 15 at spaced distances apart. These levers are pivotally connected intermediate their ends to the columns 15, and their inner ends are adapted to extend across the slots 21 when in operative position. The outer ends of each pair of levers 23 are connected by a vertical bar 24, the lower end of which is fitted with a counterweight 25. The upper ends of the levers 24 are connected by a cable 26 which is led over sheaves 27. There is sufficient slack in this cable 26 so that it may be grasped by men working on the platform 14 to swing the pairs of levers 23 about their pivotal points to latch the platform 14 in proper position.

The extreme inner ends of the levers 23 when in latching position are

adapted to rest on keepers 28 rigidly secured to the columns 15.

To elevate the platform of each scaffold unit a cable 29 is provided which is connected at its ends to opposite ends of the platform, as indicated by the numeral 30. This cable is led over blocks 31 suspended adjacent opposite ends of the beam 17. By exerting a pull on the cable 29, the platform 10 will be elevated.

In operation if it is desired to elevate the platform, a pull is exerted on the cable 29 to elevate the platform. During this time the latch levers 23 will be in unobstructing positions due to the provision of the counterweights 25, which normally hold the latch levers in the position indicated in Fig. 3. When the platform has been elevated a desired amount, a pull is exerted on the cable 20 26 to swing the latch levers to their latching positions, as indicated in Fig. 1. The cable 29 is then released so that the platform will lower slightly and the latch bars 20 of the guides 18 therefor will engage the latch levers 23 and thereby support the platform.

When the bars 20 engage the lower latch levers 23, the platform will be held in one working position. When it is desired to raise the platform to its uppermost position, a pull is exerted on the cable 29, and as soon as the guides 18 rise far enough to permit the levers 23 to swing to unobstructing positions, the weights 25 will actuate the levers and so position them. The platform is then elevated by means of the cable 29 to its uppermost position, after which a pull is exerted on the cable 26 to swing the latch levers to their latching positions so that the latch bars 20 on the guides 18 will engage the upper levers 23 and thereby support the platform in its uppermost position.

In order to gain access to the platform, one end of the platform is provided with a pivotal ladder 32 which may be positioned, if desired, as shown in Fig. 1 in full lines so that a person on the ground may ascend to the platform. When the platform is in use in its upper positions, the ladder may be folded over onto the platform, as disclosed in broken lines in Fig. 1.

It should be stated that the ends of the platform 14 of each scaffold unit project beyond the columns 15 so that planks 33 may

be supported at the ends of the platforms of both units in working position relative to 55 the ends of the car, as disclosed in Figs. 1 and 2. In this manner the workmen may easily reach any part of the car desired for repairing and painting it. When switching the cars from between the scaffold structures, 60 the planks 33 may be easily removed.

By having permanent scaffold structures on opposite sides of the trackway, repairing and painting of railway cars is facilitated.

It is apparent from the foregoing that in 65 either of its three elevations, the platform will be held in position without any danger of it accidentally lowering.

While I have shown the preferred form of my invention, it is to be understood that 70 various changes may be made in its construction by those skilled in the art without departing from the spirit of the invention, as defined in the appended claim.

Having thus described my invention, what 75 I claim and desire to secure by Letters Patent is:—

A scaffold structure for railway cars comprising a pair of vertically disposed tubular columns arranged a distance apart substantially equal to the length of a railway car, a horizontally disposed platform extending between the columns, a guide member vertically reciprocable in each column, a rigid connection between each guide member and the platform, said columns having vertical slots formed in the sides thereof, said slots being of a length equal to the vertical travel of said platform, latch bars on said guide members extending outwardly through said slots, a plurality of latch levers pivotally connected to each column and spaced apart, the inner ends of said latch levers being adapted to be disposed across said slots to engage said latch bars 95 and thereby support the platform, the outer ends of said levers being connected together and counterweighted to normally hold them in an inoperative position, and a cable connected to the outer ends of the levers of each 100 column whereby they may be operated from the platform to be disposed in latching position to engage the latch bars of the guide members.

ACHILLES FORTINA.
